UNITED STATES PATENT OFFICE.

HERBERT CHARLES BEASLEY, OF CHICAGO, ILLINOIS, ASSIGNOR TO COONLEY MANUFACTURING COMPANY, OF CHICAGO, ILLINOIS, A CORPORATION OF ILLINOIS.

ENAMELING FURNACE.

Application filed May 13, 1920. Serial No. 380,958.

To all whom it may concern:

Be it known that I, HERBERT CHARLES BEASLEY, a citizen of the United States, residing at Chicago, in the county of Cook and State of Illinois, have invented new and useful Improvements in Enameling Furnaces, of which the following is a full, clear, concise, and exact description, reference being had to the accompanying drawing,

10 forming a part of this specification.

My invention relates to enameling furnaces, and has for its object to provide a furnace of the character designated which is adapted for continuous operation and in 15 which the various portions are so arranged that uniformity of product is obtained therefrom.

At the present time the most commonly used type of enameling furnaces is of the 20 gas or coal fired muffle type, the muffle extending the entire length of the heating chamber of the furnace. The articles to which the enamel has been applied are placed in the furnace in which a temperature is 25 maintained which will fuse the enamel. After the enamel has been fused the articles are withdrawn and allowed to cool.

It is obvious that in a furnace of this type it is substantially impossible to employ a 30 continuous process. Moreover, the articles cannot be uniformly treated because of the varied degrees of temperature in the several portions of the fusing chamber.

When the articles are withdrawn from the 35 furnace and allowed to cool in the open they tend to warp and must, therefore, be straightened after being enameled. This warping tendency is also present when the articles are placed in the furnace without being pre-heated because the extreme heat of the burning chamber does not raise the temperature of the articles gradually.

One object of my invention, therefore, is to provide a furnace wherein articles 45 may be pre-heated prior to being subjected to the extreme heat of the fusing chamber. The tendency of the articles to warp is thereby reduced and a more uniform product secured while the use of a pre-heating chamber 50 wherein the waste heat is utilized effects a considerable economy in the consumption of fuel.

Another object of my invention is to provide a cooling chamber into which the articles, upon which the enamel has been

fused, are directed as they emerge from the burning chamber. In this cooling chamber the temperature is so adjusted that the articles cool uniformly and do not evince a tendency to warp. This results in a considerable saving in operation because the articles do not have to be reformed after fusing.

A furnace embodying my invention is so constructed that the articles which are continuously supplied thereto pass first through the pre-heating chamber, then the burning chamber, and finally the cooling chamber. By the use of such a continuous furnace each article passes through the same heating and cooling zones and thereby receives a more uniform treatment than is possible with the present methods, whereby articles in the rear of the furnace receive more heat than those in the front or near the door. Moreover, in a furnace of this type the articles are loaded at one end and unloaded at the opposite end whereby the confusion incidental to loading and unloading articles at the same end of the furnace, as is necessary with the present type furnace, is eliminated.

Finally the use of compartments positioned on either side of the burning chamber and having a lower temperature than that existing in said burning chamber, shields the workmen from the intense heat radiated from the burning chamber. This is of great advantage in that it prevents the exposure of the workman to the intense heat and enables one of little skill to carry out the enameling process. In the prior processes the condition of the enameled article while being fused was determined solely by the operator who had to depend on his eyesight and experience to guide him in deciding when the fusing operation was satisfactorily completed. In my process the fusing period is regulated automatically by the rate at which the articles are fed through the furnace whereby an even and uniform product is obtained.

In attaining the above objects I employ a continuous pre-heating, enamel fusing (burning) and cooling furnace. The articles are loaded outside of the furnace on pins or blades and are carried into the pre-heating chamber where they receive an initial heating from the radiation heat and waste gases coming from the openings in the

burning chamber as well as being supplied with the heat from such waste gases as are carried through a flue which extends over the pre-heating chamber.

5 The articles are then moved from the pre-heating chamber into the burning chamber where the enamel thereupon is fused. After leaving the burning chamber they pass into a cooling chamber where I arrange for cooling the same at a desirable rate by the use of water coils or other means. By the use of water coils the temperature to which the articles are cooled as well as the rate at which they are cooled may be very effectively governed by the amount and temperature of the water which is circulated through the coils.

10 For a better understanding of my invention reference may be had to the accompanying drawings, in which:

15 Fig. 1 is an elevational sectional view of an enameling furnace embodying my invention and comprising pre-heating, burning and cooling chambers taken on the line 1—1 of Fig. 2;

20 Fig. 2 is a plan view, partially in section, of the furnace shown in Fig. 1;

25 Fig. 3 is an elevational sectional view through the pre-heating chamber taken on the line 3—3 of Fig. 1;

30 Fig. 4 is an elevational sectional view through the burning chamber taken on the line 4—4 of Fig. 1; and

35 Fig. 5 is an elevational sectional view through the cooling chamber taken on the line 5—5 of Fig. 1.

40 An enameling furnace comprises walls 10 and 11 and a roof portion 12. Centrally situated in said furnace is a burning chamber 13 which is preferably heated by means of gas flame, fuel for which is supplied through pipes 14. Obviously any other suitable form of heating means could be used.

45 On one side of the burning chamber 13 is a pre-heating chamber 14' and on the other side thereof is a cooling chamber 15, the latter having associated therewith cooling coils 16. A flue 14^a extends from the burning chamber over the pre-heating chamber 14' and serves to further heat the latter.

50 Extending beneath all of the chambers is a runway portion 17 in which is positioned a track 18. A conveyor 19, provided at its upper portion with a platform 20 having thereupon pins or blades 21 which serve to hold articles 22, (runs upon the track 18), a chain 23 has hooks thereon which engage the conveyor 19 and, as the chain is moved lengthwise of the furnace by any desired means (not shown) said conveyor is moved through all the furnace chambers at any desired rate.

55 It will be observed that the chambers are so arranged that the conveyor may pass progressively therethrough whereby the ar-

60 ticles which are placed thereupon may be successively pre-heated, fused and cooled. In practicing my method of enameling, the articles to which the enamel has been applied are placed upon the pins or blades 70 21 and the conveyor passed into the pre-heating chamber 14' wherein the temperature of the articles is uniformly raised whereby the tendency for them to shrink or warp upon being subjected to the intense 75 heat of the burning chamber, is eliminated.

80 After the enamel upon the articles has been fused they are withdrawn into the cooling chamber 15 wherein the temperature is lowered at such a rate that they are uniformly cooled and do not tend to bend or warp upon being subjected to the outer air.

85 From the above description it will be observed that I have provided an enameling furnace wherein articles may be continuously supplied to one end thereof and withdrawn from the other end thereof without the workmen being subjected to the intense 90 heat of the burning chamber at either end. Moreover, the furnace is so arranged that uniformity of product is secured without their being any tendency for the articles to warp either upon being subjected to the intense heat or when they are cooled unless 95 they are quite large and made of exceedingly thin stock. When the enamel on such excessively large thin-stock articles is fused tendency for said articles to warp exists. Under these circumstances it is desirable to 100 remove these articles from the furnace in a hot condition in order to correct such warped condition. For this purpose, the water cooling coils have been provided and the temperature of the cooling chamber can be maintained at any desired temperature by regulating the flow of water in these coils, so that the temperature of the articles that are ejected from the cooling chamber can be positively determined, and the 105 same maintained hot, if desired.

110 While I have described but one embodiment of my invention it is apparent that many modifications therein may occur to those skilled in the art and I desire that it 115 be limited only by the showing of the prior art and by the scope of the appended claims.

120 Having thus described my invention, what I claim as new and desire to secure by Letters Patent is:

125 1. In an enameling furnace, a burning or fusing chamber embodying means for raising the temperature therein to an enamel fusing point, a pre-heating chamber situated at one end thereof, means for heating the latter by the waste gases from said burning chamber, a cooling chamber situated at the other end of said burning chamber, means for definitely controlling, to a predetermined degree, the temperature of 130

5 said cooling chamber to provide an optimum cooling rate therein and means comprising a carriage embodying article-supporting means and a track along which said carriage runs, associated with said chambers whereby the articles to be enameled may be continuously passed therethrough.

10 2. In an enameling furnace, a burning or fusing chamber embodying means for raising the temperature therein to an enamel fusing point, a preheating chamber situated at one end thereof, a cooling chamber situated at the other end of said burning chamber, means for passing articles successively thru the preheating chamber, fusing chamber, and cooling chamber, and means for controlling, to a predetermined degree, the cooling effect of said cooling chamber.

15 3. In an enameling furnace, a burning or fusing chamber embodying means for raising the temperature therein to an enamel fusing point, a preheating chamber situated at one end thereof, a cooling chamber situated at the other end of said burning chamber, means for passing articles successively through the preheating chamber, fusing chamber, and cooling chamber, and means for controlling, to a predetermined degree, the cooling effect of said cooling chamber, said last means comprising a conduit through which a heat-absorptive medium may be passed.

20 4. In an enameling furnace, a burning or fusing chamber embodying means for rais-

ing the temperature therein to an enamel fusing point, a preheating chamber situated at one end thereof, a cooling chamber situated at the other end of said burning chamber, means for passing articles successively through the preheating chamber, fusing chamber, and cooling chamber, and means for controlling, to a predetermined degree, the cooling effect of said cooling chamber, said last means comprising a conduit through which a heat-absorptive medium may be passed in such quantity and at such rate as to eventuate said predetermined degree of temperature in said cooling chamber.

25 5. In an enameling furnace, a burning or fusing chamber embodying means for raising the temperature therein to an enamel fusing point, a preheating chamber situated at one end thereof, a cooling chamber situated at the other end of said burning chamber, means for passing articles successively through the preheating chamber, fusing chamber, and cooling chamber, and means for controlling, to a predetermined degree, the cooling effect of said cooling chamber, said last means comprising a coil surrounding said cooling chamber and through which a cooling medium may be passed to eventuate the desired temperature therein.

30 In witness whereof, I have hereunto subscribed my name.

HERBERT CHARLES BEASLEY.
